BALANCE ASSEMBLY GAUGE

Tobias Garon, Detroit, Mich.

Application January 8, 1952, Serial No. 265,404

1 Claim. (Cl. 33—184)

1

This application discloses a Balance Assembly Gauge, particularly useful to a watchmaker for properly assembling a balance assembly.

A balance assembly includes a hair spring having a stud and hub or collet, and a roller table having a roller jewel, both mounted, with a balance wheel between them, on a balance staff. In assembling the hair spring on such staff, already having a roller table and balance wheel thereon, care must be taken in insure that the hair spring stud is positioned properly with respect to the roller jewel. The gauge hereof provides such insurance.

For a full understanding of the gauge hereof, reference should be had to the appended drawing.

In this drawing:

Fig. 1 is a top plan view, to full scale, of the gauge, with some radiating lines thereof omitted for purposes of clarity.

Fig. 2 is a part section view as if on line 2—2 of Fig. 1.

Fig. 3 is a greatly enlarged plan view showing the gauge in use, with parts omitted and fragmentarily shown for purposes of clarity.

Fig. 4 is a section view on line 4—4 of Fig. 3.

Referring now to the drawings, it will be seen that the gauge herein shown comprises a thin, gauge plate 10 formed with an integral downwardly turned flange 11 which supports plate 10 well above a work table 12 to provide a clear space 13 beneath plate 10.

Formed in plate 10 is a triangular opening 14, long and narrow, with a base 15 and sides 16 joining to define a small angle V or apex 17. On said plate is a pattern of gauge lines 18.

In the embodiment shown, the pattern of gauge lines includes sixty radiating lines, all continued to their center, a point 19 within the V and near apex 17, and disposed at six degree intervals, and numbered 1—60. For purposes of clarity, only a few are shown, and only a few of these are shown complete and numbered.

A watchmaker has an assembly comprising a balance staff 20, a balance wheel 21 and its balancing screws or pins 22 and arm or hub 23, a hair spring 24 with its stud 25, and a double roller table 26 with its safety roller 27 and its jewel 28.

The roller table may be a single plate, omitting safety roller 27, or it may be double, as shown, to include the safety roller 27. The latter form is very widely used, and is shown here, since a gauge that will accommodate a double roller plate will, of course, also accommodate a single roller plate, though the reverse is not true.

In Fig. 3, only a part of the hair spring 24 is

5 shown, the major and center part being omitted for purposes of clarity. The hair spring in its entirety simulates a flat thin disc of a diameter less than that of the balance wheel, and has a center hub or collet enabling it to be mounted on the staff 20.

10 When the watchmaker begins his work on the balance assembly, he first places such assembly on the plate in such a position that the roller table safety roller 27 enters the large base part 15 of opening 14 and then he slides the assembly around and along the plate until he has positioned jewel 28 as far as it can go into the apex 17.

15 It is noted that the apex 17 and the sides 16 of the opening 14 are so dimensioned, in relation to the size of the jewel 28 and staff 20, that with the jewel as far as it can go into apex 17, the axis of balance staff 20 approximately coincides with the center point 19. With the assembly in opening 14, the sides of such opening securely hold the assembly from laterally shifting to any appreciable extent, either because both the jewel 28 and the staff 20 are engaged by such sides, or because one of them is engaged, and the other is very close to such sides. In most cases, staff 20 will be engaged by sides 16 of opening 14, with jewel 28 very close to such sides.

20 The watchmaker, having moved jewel 28 as far into apex 17 as it can go, then notes the position of stud 25 in relation to the position of jewel 28 by noting which one of the radiating lines 18 coincides with the axis of stud 25. In Fig. 3 the stud axis is between lines 39 and 40.

25 Then the watchmaker, remembering the fact that the stud axis was at 39—40, is free to disassemble the balance assembly for repair or replacement of any part, and then to reassemble the parts, at least up to the point where he is about to restore a hair spring to a balance staff already provided with a roller table and a balance wheel. He places such assembly on the gauge, enters safety roller 27 into opening 14, and moves the assembly to seat jewel 28 in apex 17 as far as it can go. He then mounts a hair spring on the staff and moves the hair spring around until its stud 25 is positioned with its axis between lines 39 and 40. With the stud properly located, the assembly may be removed from the gauge with the assurance that stud 25 is properly located with respect to jewel 28.

30 35 40 45 50 Since it is important that the opening 14 be so shaped as to inhibit totally or almost totally any angular shifting of the assembly in such opening, and since it is important that opening 14 have an enlarged part 15 capable of receiving

the safety roller 27 of a double roller table, dimensions of one embodiment of such opening, as formed in an exemplary plate 10 of 1½ inches diameter, are here noted.

Altitude of opening 14 _____ $\frac{3}{4}$ inch

Base 15 of opening 14 _____ $\frac{3}{16}$ inch

Distance from apex 17 to

center point 19 _____ $\frac{3}{2}$ inch

Sides 16 of opening 14 _____ Equidistant from the 10 altitude, i. e., opening 14 is an isosceles triangle.

It is noted that whereas Fig. 3 shows jewel 28 in apex 17 as far as it can go, Fig. 4 shows jewel 15 28 remote from apex 17, but moving towards it, in the direction of the arrow.

Now having described the gauge hereof, reference should be had to the claim which follows:

A balance assembly gauge for watchmakers comprising a sheet metal gauge plate, and depending side flange means mounting it in a manner to provide a clear space beneath it, the gauge plate having an opening, two of whose sides join to define a V or apex of small angularity, said plate having thereon a plurality of gauge lines radiating from a point on said plate, said point from which the lines radiate being within the V

or apex of the opening, the opening having an entry portion at least large enough to permit entry therethrough from above the plate, of the safety roller portion of a double roller table of an assembly of a balance wheel, double roller table, roller jewel, hair spring, and balance staff, whereby the roller jewel of said assembly may be positioned in the V or apex of the opening, and the circular relation or position of the hair spring stud disposed above the plate, with respect to said jewel then in the apex, may be indicated by the registry of said stud, above the plate, with one or another of the various radiating lines on said plate, beneath said stud, the clear space under said plate provided by said flange being high enough to enable the safety roller of the double roller table to fit beneath the plate when the jewel thereof is within the apex.

TOBIAS GARON.
